UNITED STATES PATENT OFFICE.

JOHN GOETTEL, OF BOSTON, MASSACHUSETTS, ASSIGNOR OF ONE HALF TO
FREDERICK BALDT, OF CHESTER, PENNSYLVANIA.

CAR-WHEEL.

SPECIFICATION forming part of Letters Patent No. 363,383, dated May 24, 1887.

Application filed January 15, 1887. Serial No. 224,430. (No model.)

To all whom it may concern:

Be it known that I, JOHN GOETTEL, a citizen of the United States, residing at Boston, Suffolk county, Massachusetts, have invented 5 certain new and useful Improvements in Car-Wheels; and I do declare that the following is a full, clear, and exact description of the same, such as will enable any one skilled in the art to which this invention appertains to make 10 and use the same.

My invention relates to car-wheels which are so constructed as to allow for the slip in turning curves in the track; and its object is to provide a wheel of simple yet strong construction, all the parts being made of cast-steel, and which will turn independently of the 15 axle when necessary.

My invention consists in certain combinations and arrangements of parts, as hereinabove set forth, and particularly pointed out in the claims, reference being had to the accompanying drawings, in which—

Figure 1 is a view of the outside of one of my improved wheels. Fig. 2 is a similar view, 25 with the annular retaining-plate removed to show the arrangement of the anti-friction rollers. Figs. 3 and 6 are similar views showing other arrangements of the rollers. Fig. 4 is an enlarged vertical section of the upper 30 half of a wheel. Fig. 5 is a similar section of a modified construction.

Similar letters refer to corresponding parts in all the views.

Upon the axle A is secured a hub, B, which 35 is formed with two annular shoulders, b b' , a raised cylindrical portion, b^2 , and a circular flange, b^3 , extending from one end of the cylindrical portion b^2 , at right angles thereto. This flange is preferably arranged at the inner end of the hub B, and may be strengthened 40 by radial ribs b^4 .

The wheel C is annular, its inside diameter being somewhat greater than the diameter of the cylindrical portion b^2 of the hub. The inner face, c , of the wheel C is cylindrical and of the same thickness as the portion b^2 of the hub. Between these two cylindrical surfaces is a series of anti-friction rollers, D, cylindrical in form and of a length equal to the thickness 50 of the wheel at c . The portion b^2 of the hub thus forms the seat on which these rollers rest

and turn. They are confined in place by the flange b^3 at one end and by an annular retaining-plate, E, at the other end, which fits over the shoulder b , and is of about the same diameter as the flange b^3 . The plate E is secured by bolts E', passing through the hub B. The wheel C rests upon the rollers D between the flange b^3 and the plate E, and is therefore capable of rotating about the hub B. 60

In order to provide against the entrance of dust and grit, the wheel C is formed with two annular shoulders, c' , which project over the outer edges of the flange b^3 and plate E, as shown; and to still further guard against this 65 each face of the wheel above the shoulder c' , and the outer corners of the flange b^3 and plate E, are chamfered off to make an inclined surface, as shown, so that the cinders and dust falling upon it will slide off by their own weight. 70

The rollers D may be placed close together, as shown in Fig. 3; but I prefer to arrange them as indicated in Fig. 2, wherein the rollers are slightly separated, and a small intermediate roller, D', is placed between every two 75 rollers, D, so as to alternate with them, as shown. These intermediate rollers reduce the wear of the main rollers D on each other, and also serve an important function in distributing the lubricating material. They may be 80 used also as shown in Fig. 6, where the rollers D are set close together.

The wheel C is cored out to form an annular chamber, C', which lightens the wheel, and also serves as an oil-reservoir. In the outer 85 face of the wheel are two or more filling-holes, c^2 , closed by screw-plugs c^3 , by means of which supplies of oil can be introduced. Oil-ducts c^4 lead from the chamber C' to the inner face of the wheel c and conduct the oil to the rollers 90 D D'. Another set of oil-holes, e , is provided in the plate E, being closed by plugs e' . An oilway, d , may be formed in the rollers D and face c and seat b^2 , if desired.

In the modification shown in Fig. 5 the hub 95 B is of much greater diameter, forming practically the body of the wheel, and being cored out to lighten the wheel. The faces of the movable rim C are flush with the outer faces of the flange b^3 and plate E; but the construction is otherwise the same as that above described. 100

All the parts of this wheel are made of cast-steel, and are fitted together with a minimum of machine-work, which, in any event, is simple lathe-work. The flange b^3 is located at the rear of the wheel to resist the side-thrust of the axle when the wheel comes in contact with a curve. The nuts and oil-holes are all on the outside, where they are easily inspected and attended to.

10 The operation of my improved wheel is as follows: When running on a tangent, all the parts of each wheel revolve with the axle; but when a curve is reached the wheel on the outside of the curve can slip around on its rollers D D', 15 or the axle and hub can turn within the wheel on the inside of the curve, or both operations may take place at the same time, the result in any case being that neither wheel is compelled to slip on the track, but each rolls smoothly, 20 independent of the other. This relieves the wheels and track from the wear to which they are subjected by the slipping of wheels which are rigidly secured to the axle; and, furthermore, it saves the motive power which must 25 be expended in dragging such wheels around curves; also, thereby reducing the flange friction on curves.

Having thus described my invention, what I claim, and desire to secure by Letters Patent, is—

30 1. The combination, with hub B, having cylindrical seat b^2 , and flange b^3 , provided with ribs b^4 , of the steel rollers D D', equal in length to said seat b^2 , the plate E, secured to said hub, 35 the annular wheel C, fitted between said flange and plate and having a cylindrical face, c,

equal in width to the length of the rollers D, and provided also with shoulders $c' c'$, projecting over the edges of the flange b^3 and plate E, said shoulders and the outer corners of the 40 flange and plate being chamfered off to form an inclined surface, as and for the purpose set forth.

2. A car-wheel consisting of the combination, with hub B and annular wheel C, of the 45 steel rollers D and the intermediate rollers, D', substantially as and for the purpose set forth.

3. The combination, with the hub B, having cylindrical seat b^2 and flange b^3 , of the 50 plate E, secured to said hub, the rollers D D', resting on said seat between said flange and plate, and the wheel C, having the oil-chamber C', filling-holes c^2 , and ducts c^4 , substantially as and for the purpose set forth.

4. The improved car-wheel hereinbefore set forth, consisting of the combination of hub B, having shoulder b , seat d^2 , and flange b^3 , annular wheel C, having chamber C', face c, shoulders $c' c'$, filling-holes c^2 , and oil-ducts c^4 , 55 steel rollers D D', plate E, and bolts E', the shoulders $c' c'$, flange b^3 , and plate E being chamfered off to form an inclined surface, substantially as and for the purpose set forth.

In witness whereof I have hereunto set my hand, this 11th day of January, 1887, in the presence of two witnesses.

JOHN GOETTEL.
